(57) **CLAIM**

The ornamental design for a portion of a ceiling fan housing, as shown and described.

DESCRIPTION

FIG. 1 is a perspective view from below of a portion of a ceiling fan housing in accordance with my design;

FIG. 2 is a top plan view of the portion of a ceiling fan housing in accordance with my design;

FIG. 3 is a perspective view from the side of the portion of a ceiling fan housing in accordance with my design;

FIG. 4 is an enlarged side elevation view of the portion of a ceiling fan housing in accordance with my design, the opposite side being a mirror image of that shown;

FIG. 5 is an enlarged front elevation view of the portion of a ceiling fan housing in accordance with my design; and,

FIG. 6 is an enlarged back elevation view of the portion of a ceiling fan housing in accordance with my design.

The broken lines showing environmental structure are for illustrative purposes and form no part of the claimed design.
